US0D1059479S

(12) **United States Design Patent** (10) Patent No.: **US D1,059,479 S**
(45) Date of Patent: ** Jan. 28, 2025

(54) **FOOD STORAGE SYSTEM**

(71) Applicant: **YUM Connect, LLC**, Louisville, KY (US)

(72) Inventors: **Eric Matthew Walton**, Frisco, TX (US); **Shelby Alexis Stanfield**, McKinney, TX (US); **Peter Gerard Graham**, Lucas, TX (US); **Steven Jeffery Gluck**, Frisco, TX (US)

(73) Assignee: **Yum Connect, LLC**, Louisville, KY (US)

(**) Term: **15 Years**

(21) Appl. No.: **29/868,272**

(22) Filed: **Nov. 28, 2022**

(51) LOC (15) Cl. **07-07**

(52) U.S. Cl.

USPC **D7/610; D7/601**

(58) **Field of Classification Search**

USPC D19/26, 75, 78, 84, 86, 88, 90-92, 113, D19/135, 77; D7/354, 367, 701, 705, D7/706, 708, 550.1, 552.1, 553.1, 553.2, D7/553.7, 554.3, 554.4, 601, 602, 610, D7/600.4; D6/692
